SWITCHING MECHANISMS

George J. Lynch, Bloomfield, N. J., assignor to Mycalex Electronics Corporation, Clifton, N. J., a corporation of New York

Application April 25, 1956, Serial No. 580,524

7 Claims. (Cl. 200—11)

This invention relates to switching mechanisms and particularly to high speed mechanisms for use in tele-metering systems in which a large number of continuous switching operations must be carried out. More particularly, this invention relates to an improved brush assembly for operation in a switching mechanism of the type described.

Switching mechanisms of the type mentioned above are known in the art. The conventional types heretofore known have been unable to perform a large number of continuous simultaneous switching operations without occupying relatively large spaces and without being relatively complicated, thereby limiting their use to relatively large mechanisms. Switching mechanisms of the type described herein normally employ a commutator in association with brushes which move relative to the commutator to collectively and successively close and open a plurality of circuits. Such mechanism must be arranged to be relatively free from brush bounce during the switching operations and must have relatively uniform electrical properties in order to maintain the noise level produced by brush bounce and non-uniform electrical properties at a minimum. When the noise level exceeds a certain percentage of the signal level, the signal becomes unintelligible and thereby eliminates the possibility of supplying information to other portions of the telemetering apparatus.

As stated above, the major sources of noise in switching devices of the type described are brush or contact bounce and non-uniform electrical properties. The latter circumstance commonly arises due to the deposit of brush material on the contact material of the commutator or due to a wearing or abrading of the contact material.

One object of the present invention is the provision of a switching device of the type described which has substantially noise-free operation during a large number of switching operations.

Another object of the present invention is the provision of a new and improved brush assembly for a switching mechanism of the type described which is adapted to maintain electrically uniform properties for the switching mechanism throughout a large number of switching operations.

Another object of the present invention is the provision of a new and improved brush arm which reduces or eliminates contact bounce.

Another object of the present invention is the provision of a generally new and improved commutator and brush assembly for electrical switching mechanisms of the type described.

The above and other objects, characteristics and features of the present invention will be more fully understood from the following description taken in connection with the accompanying illustrative drawings.

In the drawings:

Fig. 1 is a side elevational view of a switching mechanism embodying the present invention with some parts

2

broken away to more clearly illustrate some of the features of the invention;

Fig. 2 is a sectional view taken along the line 2—2 of Fig. 1;

Fig. 3 is a sectional view taken along the line 3—3 of Fig. 2; and

Fig. 4 is a perspective view of a brush arm assembly embodying one of the features of the present invention.

Referring now to the drawings in detail, a switching mechanism embodying the present invention is generally designated by the reference numeral 10. Such a switching mechanism comprises a housing 12 including a base 14 and a U-shaped longitudinally extending member 16 which are held together in any suitable manner such as by screws 18. Disposed within the housing are a motor (not shown), a gear train 20 connected to the output shaft 22 of said motor, a shaft 24 which is the output shaft of the gear train, a brush assembly 26 mounted on said shaft 24 for rotation therewith and a commutator plate 28 which is in operative relationship with the brush assembly 26.

Particularly, the gear train output shaft 24 is journaled in two bearing plates 30 which are fixed to the base 14 as by screws 32 which extend through reflex portions 34 on the bearing plates 30. The commutator plate 28 comprises a modified triangular plate 36 of insulating material into which is molded a slip ring 38 and a plurality of spaced contacts 40 which are arranged in a circle concentric with said slip ring. Contacts 40 are preferably spaced from each other a distance which is much less than the width of the brushes forming part of the brush assembly 26 which will be described hereinafter. Preferably, each contact 40 is disposed as close to its adjacent contacts as is permitted by consideration of good insulation therebetween, it is believed clear that the closer the contacts are to each other, the less brush bounce there will be as the brush moves from one contact to another. The commutator plate 36 is provided adjacent its apexes with apertures 42 through which support rods 44 extend for supporting the commutator plate. The support rods 44 are fixed at each end to the bearing plates 30 whereby to hold the commutator plate in fixed relation relative to said bearing plate. For proper securing of the commutator plate to the supporting rods 44 collars 46 are mounted on the support rods and abut against adjacent surfaces of the commutator plate whereby to prevent movement of said plate longitudinally of said support rods.

Commutator plate 36 is preferably made of a vitreomericaceous material such as ceramoplastic or glass-bonded mica. This class of materials is preferred since it is the only known class of insulating material which has sufficient dimensional stability to maintain the slip ring 38 and the contacts 40 in proper spaced relationship under the range of operating conditions to which the switching mechanism is subjected. Preferably, the slip ring and the contacts are fixed to the commutator plate 36 as by molding and the commutator plate 36 has a coefficient of thermal expansion which is substantially equal to that of the slip ring and the contacts whereby to maintain the slip ring and contacts in fixed relationship throughout wide range of temperatures. The slip rings and contacts are preferably made of rhodium plated coin silver and are provided with extremely smooth pitfree surfaces.

The rhodium plating tends to resist abrading of the contact and slip ring surfaces. The contacts are each provided with a terminal 48 which extends through the vitreomericaceous plate 36 for connection with a suitable electrical conductor. The slip ring 38 is provided with at least one terminal 50 for connection with a suitable electrical conductor. It is believed obvious to those skilled

in the art that the surfaces of all the contacts 40 are coplanar and the plane defined by the surface of the contacts 40 is preferably coplanar with the surface of the slip ring 38, although this is not necessary.

As stated hereinbefore, the output shaft 24 of the gear train 20 is journaled in the bearing plates 30. Shaft 24 extends through a central aperture 51 in commutator plate 36, the central aperture being concentric with the slip ring 38 and the circle defined by the contacts 40.

According to the present invention the brush assembly 26 comprises a support member 54 having a central aperture 56 which is adapted to receive shaft 24. Adjacent the central aperture 56, support member 54 is provided with a pair of longitudinally extending slots 58 and a pair of clamping screws 60 are threadedly engaged with the member 54 and extend transversely of said member and through slots 58. It will be obvious to those skilled in the art that the support member 54 may be fixed to shaft 24 by tightening the clamping screws 60 whereby to take advantage of the resiliency of the member 54 which is preferably made of a metallic material. Fixed adjacent one end of support member 54 as by a screw 64 is a brush arm 62. Preferably, brush arm 62 is insulated from support member 54 as by an insulating washer 66 interposed between the brush arm and the support member. Brush arm 62 preferably has two angularly related portions 68 and 70, the portion 68 being adapted to carry a brush 72 and the portion 70 being provided with a terminal or binding post 74. The brush arm 62 may be made of any good conduction material such as beryllium copper, Phosphor bronze, and so forth. However, in accordance with one of the objects of the present invention, the brush arm 62 is made of two substantially coextensive portions 76 and 78, the portion 76 being made of a relatively resilient material such as spring steel and the portion 78 being made of a good conducting material such as beryllium copper. The portions 76 and 78 of the brush arm 62 are preferably joined together so as to be substantially integral as by soldering or the like throughout most of the brush arm. However, adjacent the end 80 of the brush arm 62 which end is adapted to carry the brush 72, the portions 76 and 78 are spaced from one another and a piece of resilient material such as silicone rubber or rubber is interposed between said portions 76 and 78 whereby to absorb most of the bounce caused by brush 72 moving from contact 40 to contact 40. For reasons which will become clear hereinafter, brush 72 is preferably made of a relatively soft conducting material such as silver graphite and preferably silver graphite in a range of 60% to 40% silver and 40% to 60% graphite, respectively. Most preferably, brush 72 is made of a silver graphite composition including 44% silver and 56% graphite.

Secured adjacent the opposite end of support member 54 as by a screw 84 is brush member 85 comprising a pair of angularly related brush arms 86 and 88 which carry brushes 90 and 92, respectively, both of said brushes being in sliding relationship with the slip ring 38. Brush arms 86 and 88 are preferably insulated from the member 54 as by an insulating washer 94. The brush arms 86 and 88 are preferably integral and made of any suitable conducting material such as beryllium copper although Phosphor bronze or other suitable conducting material may be employed. Of course, the arms 86 and 88 may be formed of separate pieces and joined together after manufacture thereof. Preferably, the connection between the two arms is electrically conducting whereby to maintain said arms at the same electrical potential, although one of said arms may be insulated from the other.

In accordance with the present invention, one of the brushes, preferably brush 90, is made of a relatively soft brush material, such as silver graphite. In order to obtain best results, the silver graphite should be com-

posed of between 40% to 60% silver and 60% to 40% graphite and preferably a silver graphite composition including approximately 44% silver and 56% graphite. The brush 92 is preferably made of a relatively hard brush material such as white gold although other metallic brush materials may be used. One example of a white gold composition suitable for the present application is as follows:

	Percent
Gold	56.2
Copper	22.8
Zinc	7.4
Nickel	13.6

Since, as will become more clear hereinafter when the operation of the present invention is described, the brush assembly is employed to successively close circuits between each of the contacts 40 and the slip ring 38, means must be provided to conduct electrical current from the brush arm 62 to the brush member 85. As shown herein, a wire conductor 96 is employed to perform this function. Specifically, wire 96 is connected to portion 70 of brush arm 62 as by terminal 74 and is secured in electrical conducting relationship with brush member 85 as by a terminal 98 secured to said brush member.

In operation, electrical impulses are supplied to contacts 40 and to slip ring 38. Preferably, brush 72 is proportioned to be larger than the spacing between the contacts 40 whereby it will bridge each adjacent pair of contacts as it moves from one to the other. Accordingly, if electrical impulses were supplied to adjacent contacts cross talk would result which, unless a gating circuit were employed, would be undesirable. In order to obviate the possibility of cross talk it is desirable that electrical impulses be supplied only to every other contact 40 whereby the intermediate unenergized contacts are employed merely as a bridge for the brush 72 to move from one energized contact to another. In this manner there will be no cross talk. Accordingly, when the motor is energized to rotate shaft 24 and thereby rotate the brush assembly, brush 72 will move successively from one contact to another and brushes 90 and 92 will move relative to slip ring 38 in electrical conducting sliding relationship therewith. Each time brush 72 engages an energized contact 40, a circuit will be closed through conductor 96 whereby to supply certain information to electro responsive apparatus not forming part of the invention. The novel brush assembly has been found to operate in such a manner as to prevent non-uniform conduction to arise between different portions of the slip ring 38 and the brushes 90 and 92. By eliminating the possibility of non-uniform conductive properties, one of the major sources of signal noise is eliminated. Applicant is of the belief that this highly desirable result emanates from the depositing of silver graphite on the rhodium plated coin silver graphite deposited from the brush 90 by the white gold brush 92. The depositing of the silver graphite on the surface of the slip ring appears to fill up pits or other surface irregularities on said slip ring whereby to render the entire slip ring uniform both mechanically and electrically. The white gold brush which follows the silver graphite brush, appears to sweep away any excessive amount of silver graphite deposited on the slip ring 38. Any excess of silver graphite would naturally result in irregular electrical properties and, due to subsequent contamination with foreign matter, a general increase in the resistance between the brushes and the slip ring. Brush 92 eliminates this possibility. Furthermore, the silver graphite tends to lubricate the slip ring and thereby reduce abrasion thereof. Moreover, by employing two brushes 90 and 92 in engagement with the slip ring 38, if one of said brushes for any reason were to bounce so as to increase the resistance between said brush and the slip ring 38, the probability is that the other of said brushes would

remain in electrical conducting relationship with the slip ring. Accordingly, by employing two space brushes, the variation in resistance between the brush arm 85 and the slip ring 38 resulting from brush bounce is substantially reduced from that which would normally be expected if a single brush were employed.

Another highly desirable feature of the present invention is the pressure with which the brushes engage the slip ring and contacts. Heretofore, in order to achieve long life for switches of this type, the brush pressures were maintained at an extremely low level in order to reduce possible abrading or wear on the brushes and contacts. This low contact pressure resulted in a tendency toward excessive brush bounce giving rise to extremely high noise levels. Due to the improvement in the commutating characteristics of the present telemetering switch, it has been found that the brush pressures may be greatly increased over that heretofore employed, which increase results in a substantial reduction in brush bounce and, accordingly, a reduction in noise. Specifically, it has been found that upon original fabrication of the commutating switch disclosed herein, the brush arms 68, 86 and 88 may be adjusted so that the brushes 72, 90 and 92, respectively, exert 120 pounds per square inch, 74 pounds per square inch and 68 pounds per square inch, respectively, on the contacts and slip ring. Of course, these pressures may be varied somewhat without departing from this highly desirable feature of the present invention. Thereafter, the switch may be operated for a break-in period of from one to seven days. Upon the completion of the break-in period, the brushes, contacts and slip rings are cleaned. The cleaning may be effected by manually rotating the brush assembly in a direction opposite to its normal direction of rotation (that is, manually rotating the brush assembly in a clockwise direction as viewed in Fig. 2) or by subjecting the commutating disc and brushes to a jet of compressed air or by polishing the contacting surfaces with crocus cloth or by lubricating the contacting surfaces with petroleum jelly containing finely powdered graphite, or any combination of these methods. After the contacting surfaces have been cleaned as indicated above, the switch is reassembled without any adjustment of the brush pressures and the commutator may be operated for at least one thousand hours with a substantially noise-free signal and with no further attention. At the end of this operational period, if excessive noise appears, the contacting surfaces may be recleaned and the successive periods of operation and cleaning may be observed until the brushes are no longer fit for use. Moreover, when the brushes have deteriorated to the point where they are no longer useful, it will be found that the commutator disc and particularly the contacting surfaces of the contacts 40 and slip ring 38 are still in useful condition. Accordingly, all that need be done to continue using the switch is to replace the old brush assembly with a new brush assembly.

It will be understood that the novel brush assembly disclosed herein may be used with telemetering switches now in use, replacing older and less satisfactory brush assemblies.

Although I have herein shown and described only one form of the present invention and have suggested various changes and modifications therein, it will be understood that various other changes and modifications may be made therein within the scope of the appended claims without departing from the spirit and scope of this invention.

Having now described my invention, what I claim as new and desire to secure by Letters Patent is:

1. In an electric device, a first conducting means, a second conducting means movable relative to said first conducting means, said second conducting means comprising spaced brushes in sliding moving engagement with said first conducting means along the same path thereon,

one of said spaced brushes being relatively hard and another of said spaced brushes being relatively soft.

2. In an electric device, first and second conducting means, and brush means movable relative to said first and second conducting means, said brush means including a first brush in sliding moving engagement with said first conducting means and second and third spaced brushes in movable engagement with said second conducting means along the same path thereon, said second brush being relatively hard and said third brush being relatively soft.

3. In an electric device, first and second conducting means, and brush means movable relative to said first and second conducting means, said brush means including a first brush in movable engagement with said first conducting means and second and third spaced brushes in movable engagement with said second conducting means, said second brush being relatively hard and said third brush being relatively soft, said second conducting means being harder than said second brush.

20 4. In an electric device, a first conducting means comprising a plurality of circularly arranged spaced contacts, a second conducting means comprising a ring of conducting material arranged concentrically with said first conducting means, means for insulating said first conducting means from said second conducting means, and brush means rotatably movable relative to said first and second conducting means, said brush means including a first brush in sliding engagement with said first conducting means and second and third spaced brushes in sliding relation with said second conducting means, and said second brush being made of relatively soft conducting material and said third brush being made of relatively hard conducting material.

35 5. In an electric device, a first conducting means comprising a plurality of circularly arranged spaced contacts, a second conducting means comprising a ring of conducting material arranged concentrically with said first conducting means, means for insulating said first conducting means from said second conducting means, and brush means rotatably movable relative to said first and second conducting means, said brush means including a first brush in sliding engagement with said first conducting means and second and third spaced brushes in sliding relation with said second conducting means, said second and third brushes being electrically connected to each other.

40 6. In an electric device, a first conducting means comprising a plurality of circularly arranged spaced contacts, a second conducting means comprising a ring of conducting material arranged concentrically with said first conducting means, means for insulating said first conducting means from said second conducting means, and brush means rotatably movable relative to said first and second conducting means, said brush means including a first brush in sliding engagement with said first conducting means and second and third spaced brushes in sliding relation with said second conducting means, said second brush being made of relatively soft conducting material and said third brush being made of relatively hard conducting material, said second and third brushes being electrically connected to each other.

55 7. In a commutating device having a commutator disc including a contact ring provided with terminal means, a plurality of spaced contacts arranged in a circle spaced from and concentric with said contact ring, one of said contacts having another terminal means associated therewith, said contact ring and said spaced contacts being molded in a plate formed of vitreous-micaceous material whereby to insulate said spaced contacts from each other and from said contact ring, and a rotatable shaft concentric with said contact ring; brush means for successively connecting said spaced contacts to said contact ring, comprising a member fixed to said shaft for rotation therewith, a first brush arm carried by said member for rotation therewith, a first brush carried by said first brush arm and being successively slidably electrically engage-

able with said spaced contacts, a second brush arm having a pair of angularly related parts, each of said parts carrying a brush thereon, said second brush arm being carried by said member for rotation therewith, said brushes being carried by said second brush arm being spaced from one another and being in sliding engagement with said contact ring, one of said brushes on said second brush arm being relatively soft and the other of said brush arms on said second brush being relatively hard.
